United States Patent Office.

J. R. KELSO, OF FREEDOM, MISSOURI, ASSIGNOR TO HIMSELF AND ERNEST QUAST, OF SAME PLACE.

Letters Patent No. 91,345, dated June 15, 1869.

IMPROVEMENT IN GUN-CARRIAGES.

The Schedule referred to in these Letters Patent and making part of the same.

To all whom it may concern:

Be it known that I, J. R. KELSO, of Freedom, in the county of La Fayette, and State of Missouri, have invented a new and useful Improvement in Gun-Carriages; and I do hereby declare that the following is a full, clear, and exact description thereof, which will enable others skilled in the art to make and use the same, reference being had to the accompanying drawing, forming part of this specification.

This invention relates to improvements in gun-carriages, and apparatus for training the same, designed to provide an arrangement whereby the gun may be trained to any desired direction more readily than can be done by the means at present in use.

The invention consists in a carriage swivelled at each end upon supports, arranged in ways or on tracks crossing each other at right angles, in such a manner that as the said supports are moved forward or back in their respective ways, the gun may be turned to any required direction, as hereinafter more fully specified.

The drawing represents a perspective view of my improvement.

A represents the carriage, or the main portion thereof, whereon the part B, upon which the trunnions of the gun are borne, may be arranged to slide to and fro in any preferred manner.

The said part A is swivelled at each end to the benches or supports C and D, so as to turn freely thereon, by pivot-bolts E.

These benches are supported on runners C' and D', fitted to dovetail grooves in the foundation, the grooves for one set of runners being at right angles to those of the other.

The runners may be provided with rollers to reduce the friction, or the rollers may be arranged in the bottom of the grooves.

Instead of the grooves, rails may be employed, and the runners fitted to the rails, or provided with wheels to run thereon.

By this arrangement, when one end of the carriage is moved away from the centre of the foundation, the other end will be brought towards it, but from a direction at right angles to that in which the receding end moves. The movement of the receding end will be arrested when the other arrives at the centre; and if the latter be moved across the centre, and away from it in the opposite direction, that end which was receding will be brought back towards the centre.

This motion changes the direction of the gun, and may be continued, to cause the gun to point in all directions horizontally, as will be readily understood, and furnishes a very simple means for training heavy guns, whether on shipboard or in fortifications.

Any preferred form or arrangement of the supports may be employed.

Having thus described my invention,

I claim as new, and desire to secure by Letters Patent—

The carriage, swivelled or otherwise mounted upon supports at each end, arranged to traverse in grooves or upon ways at right angles to each other, substantially as specified.

J. R. KELSO.
